(57) **CLAIM**

The ornamental design for a flashlight recharger, as shown and described.

DESCRIPTION

FIG. 1 is a rear and top left perspective view of a flashlight recharger.

FIG. 2 is a front and top right perspective view of the flashlight recharger.

FIG. 3 is a top plan view of the flashlight recharger.

FIG. 4 is a front view of the flashlight recharger.

FIG. 5 is a rear view of the flashlight recharger.

FIG. 6 is a left side view of the flashlight recharger, in which the broken line showing of the flashlight is included for the purpose of illustrating environmental elements only and forms no part of the claimed design; and,

FIG. 7 is a right side view of the flashlight recharger.
